HYDRAULIC SEALING MACHINE

Walter Lee Owens, Chesterfield, Ind., assignor to
 Robert W. Shoemaker, Anderson, Ind.

Application December 3, 1941, Serial No. 421,465

8 Claims. (Cl. 81—9.1)

The invention relates to the banding or binding of metal sheets, and other material, into packages for convenient handling and shipping, and more particularly to a machine for fixing seals upon the overlapped ends of the bands with which the packages are bound.

Sheets of steel are usually shipped from the mill in packages or bundles bound with steel bands or straps, the ends of which are connected together by sheet metal seals, and the present invention pertains to machines for attaching said seals to the bands.

These steel bands may be stretched around the bundle or package of sheets, or other material, by any suitable banding machine, which may be of the type disclosed in my United States Letters Patent No. 2,247,398, dated July 1, 1941, by means of which the bands are strapped tightly around the bundle with the ends of the bands overlapped to receive sheet metal seals which are usually crimped upon the overlapped ends of the bands, by a sealing machine, to hold the bands tightly bound around the package.

Such sealing machines as are now in general use for this purpose are very large, heavy and cumbersome, requiring the workman to use both hands in operating the same, necessitating one man to operate the banding machine to stretch a band around the package and another man to operate the sealing machine.

This is particularly true of the sealing machines used for sealing the larger bands of approximately two inches in width, the sealing machines customarily used for such purpose weighing about thirty pounds and having two heavy operating levers, each several feet in length.

A further objection to the customary sealing machines is that, due to the fact that they are constructed so as to crimp or cut the seal and band downward toward the package, it is difficult, and sometimes almost impossible, to operate them in case the band and seal are flattened tightly against the package.

Furthermore the sealing machines used under present practice are hand operated, mechanical devices, frequently requiring considerable effort to operate.

The present invention contemplates the provision of a hydraulic sealing machine designed to overcome the objections to the present type of sealing machines.

Another object of the invention is to provide a sealing machine for operating upon the largest size seals and which weighs considerably less than the machines now in use for the purpose.

A further object is the provision of a hydraulic sealing machine of relatively light weight and constructed so as to be operated with one hand, leaving the other hand free to operate a banding machine.

A still further object of the invention is the provision of a band sealing machine constructed so as to cut the seal and band upward, and having tapered jaws arranged to be inserted under the edges of the seal so that it will operate satisfactorily even though the band and seal are located tightly against the package.

Another object is the provision of a sealing machine of the type referred to in which cutting knives are carried upon opposed, pivoted jaws having tapered lips arranged to engage beneath opposite side edges of the seal.

Still another object is the provision of a sealing machine of the hydraulic type in which the pivoted jaws are operated through toggle levers operatively connected to the ram or piston of a hydraulic cylinder.

A further object is the provision of such a hydraulic sealing machine in which the pivoted jaws are pivotally mounted upon the sides of the hydraulic cylinder and a die is fixed upon the lower end of the cylinder for clamping and mashing down the central portion of the seal and band during the operation of the machine.

A still further object of the invention is the provision of a machine of this type so constructed that it will be held in a vertical position upon the package and having a handle grip by means of which the machine may be easily carried with one hand.

Still another object is the provision of a sealing machine having a knife for scoring the band transversely, so that the loose end of the band may be easily broken after the seal is affixed.

The above objects together with others which will be apparent from the drawings and following description, or which may be later referred to, may be attained by constructing the improved hydraulic sealing machine in the manner illustrated in the accompanying drawings, in which—

Figure 1 is a side elevation of the improved hydraulic sealing machine with the jaws in the open or normal position;

Fig. 2, a front elevation of the machine in the position shown in Fig. 1;

Fig. 3, a top plan view of the machine with the jaws in the closed or operated position;

Fig. 4, a bottom plan view of the machine with the jaws in the open position as shown in Figs. 1 and 2;

Fig. 5, a vertical sectional elevation of the machine showing the jaws in closed position;

Fig. 6, a fragmentary elevation of the inner side of one jaw;

Fig. 7, a fragmentary sectional view showing the scoring blade;

Fig. 8, a detail perspective view of one of the cutting knives;

Fig. 9, a detached perspective view of one of the sheet metal seals;

Fig. 10, a fragmentary perspective view of a portion of the overlapped ends of a band showing the seal placed thereon in position for sealing; and

Fig. 11, a view similar to Fig. 10 after the seal and band have been cut and sealed by the improved hydraulic sealing machine.

Similar numerals refer to similar parts throughout the drawings.

The hydraulic sealing machine to which the invention pertains is operated by means of a hydraulic jack of any usual and well-known construction, comprising the cylinder 15 having the ram or piston 16 therein arranged to be operated by the hydraulic pump 17 which is mounted upon the base 18 carrying the cylinder, a valve 19 of any usual and suitable construction being provided for controlling the communication between the pump and the cylinder as in usual and well-known practice.

The pump 17 is provided with the usual operating handle 20 pivotally connected as at 21 to the plunger of the pump and having its inner end pivotally connected as at 22 to the links 23 pivoted at their lower ends to the base 18 as indicated at 24.

A pair of similar jaws 25 is pivotally mounted between the depending spaced flanges 26 rigidly connected to the underside of the base 18 of the jack. For this purpose each jaw may have an inwardly disposed boss 27 extending between the depending flanges 26 and having a bearing opening 28 receiving the adjacent bolt 29 upon which the jaws are pivoted.

Each jaw 25 has a pair of cutting knives 30 mounted thereon, the knives being preferably formed upon the pins 31 received in suitable openings 32 in the jaws. The cutting edge portion of each of these knives is located within an angular, lateral recess 33 in the inner face of the jaw, terminating at its lower end in the tapered inwardly disposed lip 34.

Each jaw has an integral upwardly disposed lever portion 35 formed thereon and preferably provided with spaced notches 36 at its upper end for a purpose to be later described.

A dual, inverted U-shape bracket 37 is fixed upon the upper end of the ram or piston 16 of the jack and provided with a pair of depending arms 38 extending down along the forward side of the cylinder 15 and outwardly disposed at their lower ends as at 39, and a pair of spaced parallel arms 40 extending down along the rear side of the cylinder and straddling the pump 17.

Links 41 are pivotally connected to the lower ends of the arms 38 and 40, as indicated at 42, the upper or outer ends of said links being received in the spaced slots 36 at the upper ends of the lever arms 35, and pivotally connected thereto as shown at 43.

A cross arm 44 may be fixed to the upper portion of the U-shape bracket 37 as by the screws 45 and coil springs 46 are connected to opposite ends of said cross bar at their upper ends and to pins 47, upon the base 18, at their lower ends.

for the purpose of pulling the ram or piston 16 of the jack down to normal position when the valve 19 is operated to release the piston.

A block or anvil 48 is rigidly mounted below the base 18 and provided with the flange portion 49 extending between the spaced cutting knives on the jaws and adapted to clamp and mash the central portion of the seal downward while at the same time the lower ends of the depending flanges 26 clamp and hold down the ends of the seal during the cutting or sealing operation.

For the purpose of holding the sealing machine in upright position upon a package to be sealed a rigid arm 50 is connected to the underside of the base 18 and terminates at its free end in the down turned portion 51 having a foot 52 which may be of rubber or the like adapted to rest upon the top of the bundle.

A handle grip 53 may be connected to the stirrup 54 fixed to the upper end of the dual, U-shape bracket 47 for the purpose of carrying the machine around the mill and placing it in position upon a bundle to be banded and sealed.

For the purpose of operating the valve 19 to release the jack ram or piston 16, when the same has been raised to the necessary height, a chain or other flexible member 55 may be connected to the cross arm 44 and to an angular arm 56 upon the valve stem.

Means may be provided for scoring the protruding end portion of the band after the sealing operation in order that the end of the band may be severed at this point. For this purpose the scoring blade 57, provided with a serrated scoring edge 58, is carried on the lower end of the operating lever 59 journaled upon the eccentric 60 which is pivotally mounted upon the bolt 61 carried by the adjacent depending flange 26.

A lever 62 is fixed upon the eccentric and when located in the position shown in Fig. 2 raises the scoring blade out of contact with the band. When the lever 62 is thrown to the position shown in Fig. 7 the eccentric 60 is rotated upon the bolt 61 to lower the scoring blade so that the same will contact with the band.

A latch member 63 is pivoted upon the lever 59 as at 64 and provided with a socket 65 adapted to receive the head 66 of the lever 62 upon the eccentric, thus locking the eccentric in position to hold the scoring blade lowered against the band. The lever handle 59 may then be operated to score the loose end of the band so that the same may be easily broken off at this point.

A pair of coil springs 67 may be provided for normally holding the lever 59 in vertical position, one of these springs being connected to each side of the lever as shown at 68 and to the adjacent side of the base 18 as at 69.

In forming a package of sheets or the like one or more metal bands or straps, as indicated at 70, may be placed around the package with the overlapped ends thereof inserted through a sheet metal seal 71, and the band is drawn tightly around the package by any suitable form of banding machine or tool.

The improved sealing machine is then placed over the seal 40 in the open position, as shown in Fig. 2, and the pump is operated by the handle 20 raising the ram or piston 16 in the cylinder so that through the U-shape member 38, links 41 and lever arms 35 the jaws 25 are moved toward each other as shown in Fig. 5, engaging the tapered lips 34 under opposite edges of the seal, the cutting edges 30 of the knives cutting oppo-

site edge portions of the seal, and band, at spaced points as indicated at 72 in Fig. 11.

The beveled surfaces 73 of the cutting knives at the same time bend the edge portions of the seal and band upward at the outer sides of the cuts, as shown at 74, while the flange portion 49 of the block 48, and the lower ends of the depending flanges 26, clamp and mash down the central portion of the seal between the cuts, as indicated at 75, and the end portions of the seal, as indicated at 76, thus sealing the band while it is tightly stretched around the package so that it cannot be removed unless it is severed by shears or the like.

In order to then remove the loose end of the band the eccentric 60 may be operated by the lever 62 to lower the serrated edge of the scoring blade 57 into contact with the band. The pivoted latch member 63 is then dropped down so that the head 66 of the lever 62 is received in the socket 65 of said latch member and the lever handle 59 is swung back and forth causing the serrated edge of the scoring blade to score the end portion of the band sufficiently so that it may be broken off at this point.

From the above it will be seen that the improved hydraulic sealing machine may be easily and quickly operated with one hand, to cut and seal large size seals more easily and readily than the large, heavy and cumbersome sealing machines now in use for such purpose, while the operator may use his other hand to operate the banding machine to hold the band stretched tightly around the package while it is being sealed.

I claim:

1. A hydraulic sealing machine for fixing a seal upon the overlapped ends of a band, said machine including a hydraulic cylinder, a ram in the cylinder, means for admitting fluid to the cylinder, a pair of jaws pivotally mounted below the cylinder, spaced cutting knives diverging upwardly from the lip of each of the jaws, upwardly disposed lever arms fixed upon the jaws, an inverted U-shape bracket carried by the ram and links pivotally connecting the lever arms to the U-shape bracket.

2. A hydraulic sealing machine for fixing a seal upon the overlapped ends of a band, said machine including a hydraulic cylinder, a ram in the cylinder, means for admitting fluid to the cylinder, a pair of jaws pivotally mounted below the cylinder, spaced cutting knives diverging upwardly from the lip of each of the jaws, upwardly disposed lever arms fixed upon the jaws, an inverted U-shape bracket carried by the ram and links pivotally connecting the lever arms to the U-shape bracket, and spring means for normally urging the ram downward in the cylinder.

3. A hydraulic sealing machine for fixing a seal upon the overlapped ends of a band, said machine including a hydraulic jack comprising a cylinder with a ram therein, a pump for operating the ram and a valve controlling the flow of fluid between the pump and cylinder, a pair of jaws pivotally mounted below the jack, cutting knives upon the opposed surfaces of the jaws, upwardly disposed lever arms fixed upon the jaws, means including links pivotally connecting the lever arms to the ram and means operatively connected to the ram and to the valve and operated by the raising of the ram for operating the valve to release the ram when said ram is raised to a predetermined height.

4. A hydraulic sealing machine for fixing a seal upon the overlapped ends of a band, said machine including a hydraulic jack comprising a cylinder with a ram therein, a pump for operating the ram, a valve controlling the flow of fluid between the pump and cylinder, a pair of jaws pivotally mounted below the jack, cutting knives upon the opposed surfaces of the jaws, upwardly disposed lever arms fixed upon the jaws, means

5. including links pivotally connecting the lever arms to the ram, and a flexible member connected at opposite ends to the ram and to the valve for operating the valve to release the ram when said ram is raised to a predetermined height.

15 5. A hydraulic sealing machine for fixing a seal upon the overlapped ends of a band, said machine including a hydraulic jack comprising a cylinder with a ram therein, a pump for operating the ram, a valve controlling the flow of fluid

20 between the pump and cylinder, a pair of jaws pivotally mounted below the jack, cutting knives upon the opposed surfaces of the jaws, upwardly disposed lever arms fixed upon the jaws, an inverted U-shape bracket carried by the ram, links

25 pivotally connecting the lever arms to the U-shape bracket, a valve controlling the flow of fluid between the pump and cylinder, and means operatively connected to the U-shape bracket and to the valve and operated by the raising of the

30 ram for operating the valve to release the ram when said ram is raised to a predetermined height.

6. A hydraulic sealing machine for fixing a seal upon the overlapped ends of a band, said machine including a hydraulic jack comprising a cylinder with a ram therein, a pump for operating

35 the ram, a valve controlling the flow of fluid between the pump and cylinder, a pair of jaws pivotally mounted below the jack, cutting knives upon the opposed surfaces of the jaws, upwardly

40 disposed lever arms fixed upon the jaws, an inverted U-shape bracket carried by the ram, links pivotally connecting the lever arms to the U-shape bracket, a valve controlling the flow of

45 fluid between the pump and cylinder, and means operatively connected to the U-shape bracket and to the valve and operated by the raising of the ram for operating the valve to release the ram when said ram is raised to a predetermined height and spring means for normally urging the ram downward in the cylinder.

7. A hydraulic sealing machine for fixing a seal upon the overlapped ends of a band, said machine including a hydraulic jack comprising a cylinder with a ram therein, a pump for operating

55 the ram, a valve controlling the flow of fluid between the pump and cylinder, a pair of jaws pivotally mounted below the jack, cutting knives upon the opposed surfaces of the jaws, upwardly

60 disposed lever arms fixed upon the jaws, an inverted U-shape bracket carried by the ram, links pivotally connecting the lever arms to the U-shape bracket, a valve controlling the flow of

65 fluid between the pump and cylinder, and a flexible member connected at opposite ends to the U-shape bracket and to the valve for operating the valve to release the ram when said ram is raised to a predetermined height.

8. A hydraulic sealing machine for fixing a seal upon the overlapped ends of a band, said machine including a hydraulic jack comprising a cylinder with a ram therein, a pump for operating

70 the ram, a valve controlling the flow of fluid between the pump and cylinder, a pair of jaws pivotally mounted below the jack, cutting knives

upon the opposed surfaces of the jaws, upwardly disposed lever arms fixed upon the jaws, an inverted U-shape bracket carried by the ram, links pivotally connecting the lever arms to the U-shape bracket, a valve controlling the flow of fluid between the pump and cylinder, and a flexible member connected at opposite ends to the

U-shape bracket and to the valve for operating the valve to release the ram when said ram is raised to a predetermined height and spring means for normally urging the ram downward in the cylinder.

6 WALTER LEE OWENS.
